UNITED STATES PATENT OFFICE

FERDINAND SCHMIDT, OF DES MOINES, IOWA

DESIGN FOR A GOBLET OR SIMILAR ARTICLE

Application filed May 7, 1929. Serial No. 31,127. Term of patent 7 years.

To all whom it may concern:

Be it known that I, FERDINAND SCHMIDT, a citizen of the United States, and a resident of Des Moines, in the county of Polk and State of Iowa, have invented a certain new, original and ornamental Design for a Goblet or Similar Article of which the following is a specification, reference being had to the accompanying drawing forming part thereof.

Figure 1 is a side elevation of a goblet or similar article embodying my design; and

I claim:

The ornamental design for a goblet or similar article as shown.

FERDINAND SCHMIDT,
